Specification for Design.

Patented June 21, 1921.

Application filed September 23, 1920. Serial No. 412,400. Term of patent 3½ years.

To all whom it may concern:

Be it known that I, WILLIAM A. McCOLLOUGH, a citizen of the United States of America, residing at Webster City, in the county of Hamilton and State of Iowa, have invented a new, original, and ornamental Design for a Drinking-Pan for Stock-Fountains, of which the following is a specification, reference being had to the accompanying drawing, forming part thereof.

Figure 1 is a perspective view of a drinking pan for stock fountains, showing my new design. Fig. 2 is a plan and Fig. 3 an end elevation of the same, on a reduced scale.

I claim:

The ornamental design for a drinking pan for stock fountains, as shown.

WILLIAM A. McCOLLOUGH.
